APPARATUS FOR IMPRESSING TRANSFER DESIGNS UPON POTTERY BLANKS

Norman Victor Germany, Leicester, England, assignor to United Shoe Machinery Corporation, Flemington, N. J., a corporation of New Jersey

Application December 18, 1948, Serial No. 66,111

15 Claims. (Cl. 41—1)

1

This invention relates to apparatus for use in ornamenting work pieces and more particularly to apparatus for impressing paint from a transfer upon a pottery blank.

In the manufacture of ceramic ware, such for example as earthenware plates and dishes, in accordance with a common procedure, a moist material having a clay basis is first shaped in accordance with the shape of the article to be made and is then dried. At this stage the material is in a very fragile condition and has little or no water resistance but would rapidly disintegrate if immersed in water. Its outer surface may, if desired, be carefully smoothed down by hand using a suitable abrasive. The material is then fired at a temperature of the order of 1100° C. to provide a blank which is relatively strong and water resistant but may be somewhat rough and porous. The blank is freed from dust and loose particles and is then in condition to be ornamented and glazed.

It is common to ornament such a blank by the use of a transfer of a type comprising a sheet of thin paper or similar material carrying on one side a pattern executed in a suitable coloring matter or paint. The painted side of the transfer may be applied to the blank by hand and pressed into smooth and intimate contact with the blank by the use of a piece of soft felt or flannel and a little soft soap may be used as an emollient. Subsequently a process which is sometimes referred to as "rubbing-on" is effected causing the paint to be impressed upon the rough and porous blank so that when the blank is dipped in water and the paper is removed from the blank by hand the paint remains on the blank and little or none is removed with the paper. Following removal of the transfer paper the blank is fired at a temperature of the order of 600° C. to burn out any oil in the paint so that it will have no adverse effect during subsequent glazing.

The process referred to as "rubbing-on" has in the past been customarily effected by hand by employing a stiff bristled brush-like tool which is applied to the transfer-coated blank with a severe rubbing action. This action requires considerable skill and manual effort and there is always a possibility that the operation may be performed inadequately so that an undesirably large quantity of the paint is subsequently removed with the paper or is removed unevenly so that the paint is not well impressed on the blank at all parts thereof.

It is an object of the present invention to provide improved apparatus for impressing paint

2

from a transfer upon a pottery blank, the apparatus being fast, reliable, and requiring little skill on the part of the operator.

As illustrated herein the work is acted upon by a pair of flexible, impervious diaphragms between which the work is placed, the diaphragms being carried by supports which form with the diaphragms chambers into which pressure fluid is introduced to force the diaphragms toward each other. One of the supports is arranged for movement toward and away from the other to move the diaphragms together or to separate them, placing of the work therebetween being facilitated by separating the diaphragms. To insure against rupture of the diaphragms when pressure fluid is admitted into the chambers formed by the diaphragms and their supports, and in accordance with a feature of the invention, provision is made for preventing admission of the pressure fluid into the chambers until the movable support has been moved to carry its diaphragm into operative relation to the diaphragm on the other support.

To insure intimate contact between the diaphragms and the work and in accordance with another feature of the invention, air is exhausted from the space between the diaphragms prior to the admission of pressure fluid into the chambers, there being a sealing ring associated with one of said diaphragms which cooperates with the other diaphragm to form a closed work chamber therebetween when the diaphragms are in operative positions relatively to a work piece.

The movable diaphragm support is arranged to be moved toward the other support by pressure fluid, there being a valve movable into different positions to cause movement of the diaphragm support, to exhaust air from the space between the diaphragms and to admit pressure fluid into the chambers to force the diaphragms into engagement with the work. In accordance with a further feature of the invention, mechanism is provided to insure completion of each step in the operation in the sequence as stated above before the valve can be moved to initiate the next step in the operation.

It may be desirable to spray with water that diaphragm which acts directly on the transfer, prior to the application of pressure by the diaphragms to the work. To this end and in accordance with a still further feature of the invention a spray nozzle is provided which may be directed toward that diaphragm which is arranged to engage the top of the work, there being means for automatically admitting water to said

spray nozzle momentarily in the movement of the movable diaphragm toward the other diaphragm. It may be desirable to provide a second spray nozzle by which water may be directed onto the lower diaphragm in those instances in which transfers are to be placed on opposite sides of the work and in this event automatic operation of the sprays may be eliminated and the sprays operated manually so that the diaphragms may be wet before the work is placed on the lower diaphragm.

The above and other features of the invention including various details of construction and novel combinations of parts will now be described by reference to the drawings and pointed out in the claims.

In the drawings,

Fig. 1 is a front elevation of one form of machine embodying the invention;

Fig. 2 is a side elevation of the machine shown in Fig. 1;

Fig. 3 is a detail view on a larger scale of a portion of the mechanism for operating a water supply valve;

Fig. 4 is a vertical section through the lower portion of the machine;

Fig. 5 is a detail view of a latch associated with the main control valve;

Fig. 6 is a view of the latch of Fig. 5 in a different position;

Fig. 7 is a front elevation of mechanism for controlling the operation of the valve;

Fig. 8 is a developed sectional view of the mechanism shown at the upper portion of Fig. 7;

Fig. 9 is a section through the valve controlling the suction line by which air is exhausted from the space between the diaphragms;

Fig. 10 is a section of a portion of a pair of diaphragms for operating upon a plate, and

Fig. 11 is a view similar to Fig. 10 of a pair of diaphragms designed for operation on a cup.

As shown in Fig. 4 the work is operated upon by a pair of diaphragms 10 and 12, the diaphragm 10 forming the top wall of a pressure chamber 14 the other walls of the chamber being formed by a box 16. This box has an outwardly extending flange 18 near its upper end against which the marginal portions of the diaphragm 10 are clamped by a ring 20 and screws 22. The diaphragm 12 is similarly clamped to a disk or support 24 having a downwardly extending flange 26 over which the diaphragm is stretched so that a chamber 28 is formed between the diaphragm 12 and the support 24. With the diaphragms in operative relation to a work piece such as a plate P air is exhausted from the space between the diaphragms through a pipe 30 which communicates by way of a port 32 (Fig. 10) in a ring 34 which seats on the lower diaphragm 10 and is located in position by the heads of the screws 22. The ring 34 forms, with the diaphragms, a closed chamber as shown in Fig. 4. After the air has been exhausted from between the diaphragms, pressure fluid such as air is admitted into the chambers 14 and 28 as will be herein-after explained, to force the diaphragms under high pressure into contact with the opposite faces of the work.

The box 16 carrying the lower diaphragm 10 is supported on a base 36 and is secured thereto by clamps 38 (Fig. 1). Carried by and extending upwardly from the base at opposite sides of the box 16 are supporting posts 40 for a slide 42 provided with bearing sleeves 44 which have a sliding fit with the posts 40. The upper

ends of the posts 40 are interconnected by a crosshead 46 which also is connected to a hollow post 48 (Fig. 2) extending upwardly from the base at the rear of the box 16.

The support 24 for the upper diaphragm 12 is carried by the slide 42. For securing the support to the slide the support is provided with upwardly extending ears 50, 52, 54 (Fig. 1). The ears 50, 52 are located rearwardly of the ear 54 and are hooked over pins 56 carried between ears 58 depending from the slide 42. The ear 54 is held by a removable pin 60 carried by spaced ears 62 depending from the slide 42.

The slide 42 carrying the upper pressure chamber is normally held in a raised position as shown in Figs. 1 and 2. For this purpose the slide 42 has connected thereto a chain 64 which passes upwardly over a pair of pulleys 66 journaled in the crosshead 46 and then passes down into the hollow post 48. The lower end of the chain is secured to the upper end of a tension spring 68, the lower end of which is secured at 70 (Fig. 4) to the lower end of the post 48, the posts 40 carrying adjustable collars 72 for limiting the upper position of the slide 42 under the action of the spring 68.

For moving the support 42 downwardly after a work piece has been placed on the lower diaphragm 10 the crosshead 46 carries a depending tube 74 (Fig. 2) within which operates a plunger 76 engaging an abutment 78 on the slide 42. The upper end of the plunger has formed thereon a piston 80 which fits within the upper end of the tube 74 so that upon the admission of pressure fluid into the upper end of the tube by way of a pipe 82 the plunger 76 forces the slide 42 downwardly to carry the support 24 and its diaphragm 12 into sealing engagement with the ring 34 and into operative relation to the work.

Extending outwardly from the bearing sleeves 44 are bosses 84 to which are pivoted downwardly extending links 86. The lower ends of these links are pivotally connected between arms 88, 90, the arms 88 being connected to the outer ends of a shaft 92 journaled in the base 36 and the arms 90 being carried by pins 94 which are in axial alignment with the shaft 92. The arrangement is such that upon movement of the slide 42 from its upper to its lower position the shaft 92 is turned through 180° and is turned in the opposite direction back to its original position upon return movement of the slide 42 to its upper position, the purpose of which will appear as the description proceeds.

Air is admitted into the upper pressure chamber 28 through a flexible tube 96 the upper end of which is secured to a nipple 98 which communicates with a passage 100 in a fitting 102 threaded into the slide 42. This fitting has a smooth bearing surface which engages a complementary bearing surface on the support 24 having a passage 104 communicating with the passage 100 in the fitting 102. The pressure fluid is admitted into the lower chamber 14 through a pipe 106, a passage 108 formed in the contacting surfaces of the base 36 and box 16, and a port 110 in the bottom wall of the box. For controlling the admission of pressure fluid into the chambers 14 and 28 by way of pipes 106 and 66 a control valve 112 is provided. This valve includes a valve housing 114 fitted into the front wall of the base 36 and providing a chamber for a slide valve member 116 provided at its outer end with a knob 118 by which the slide valve member 116 is moved rearwardly. The slide valve

member is normally urged forwardly by a spring 120 surrounding a stem projecting rearwardly from the slide valve member, this spring acting between a bracket 122 depending from the top wall of the base 36 and a collar 124 secured to the valve stem which projects rearwardly from the housing 114.

The valve member 116 includes an element 126 which normally prevents flow of pressure fluid such as air from an inlet pipe 128 to outlet pipes 130, 132. The pipe 128 may be connected to any suitable source of pressure fluid such as a pump (not shown). The pipe 130 is connected to a cylinder 134 secured to the underside of the base and movable in which is a piston 136 having a forwardly extending piston rod 138, the purpose of which will appear as the description proceeds. The pipe 132 is connected to the pipe 96 through which pressure fluid is directed to the upper pressure chamber 28 and is also connected to the pipe 106 by which the fluid is conducted into the lower pressure chamber 14.

With the machine not in operation and the valve member 116 in its forwardmost position the collar 124 is located just forwardly of a pawl 140 carried by the shaft 92. This pawl is mounted on the shaft for turning movement relatively thereto and also for movement therewith. As shown in Fig. 7 a collar 142 is secured to the shaft 92 to the left of the pawl 140. The pawl has a bore therethrough parallel to the shaft 92 in which are two hardened steel balls 144, 146 maintained in separated positions as shown in Fig. 7 by a spacing block 148. Secured to a bearing 150 for the shaft 92 is a facing piece 152 engageable with the right side of the pawl 140. The ball 144 engages the collar 142 and the ball 146 is engageable with the facing piece 152.

When the machine is not operating, the pawl 140 occupies the position shown in Fig. 5 as stated heretofore and cooperates with the collar 124 to prevent rearward movement of the valve member 116. At this time the ball 146 occupies a shallow radial V-shaped groove 154 in the facing piece 152, thus holding the pawl 140 against rotation. When, however, the support 24 is moved downwardly by the admission of pressure fluid through the pipe 82 (Fig. 2) and the shaft 92 is rotated through approximately 160° from the position of Fig. 5, during which time the pawl 140 remains stationary, a groove 156 in the collar 142 moves into register with the ball 144 while at the same time a pin 158 fixed to the collar 142 moves into engagement with a pin 160 projecting laterally from the pawl 140. During the remaining 20° of rotation of the shaft 92 the pawl 140 by reason of the engagement of its pin 160 with the pin 158 will move with the shaft swinging the pawl 140 into the position shown in Fig. 6. During this movement of the pawl 140 the ball 146 moves out of the groove 154 which movement is permitted by reason of movement of the ball 144 into the groove 156 in the collar 142 and thus the collar and the pawl are locked together.

Mounted on the left side of the base 36 is a valve 162 which normally prevents communication between the pipe 82 and a pipe 164 connected to a source of pressure fluid. After a work piece is inserted in the machine a lever 166 of the valve is depressed to connect the pipes 164, 82, whereupon the slide 42 is forced downwardly as heretofore explained and the shaft 92 is turned through 180° during the last portion of which the pawl 140 is moved from the position of Fig. 5

70 75

into the position shown in Fig. 6. The operator may now move the valve member 116 rearwardly until the collar 124 engages a vertically slidable stop 168 at which time the pipe 130 is in communication with the pipe 128 but the pipe 132 is still not in communication therewith. The piston rod 138 is provided with a bore 170 extending diametrically therethrough and providing communication when the piston has moved forwardly as shown in Fig. 4 between the pipe 39 and a pipe 172 (Fig. 9) connected with a suitable vacuum pump (not shown). The pipes 30 and 172 communicate with ports 174, 176 in a block 178 which forms the forward wall of the cylinder 134 and these ports communicate with each other through the port 170 in the piston rod 138 with the piston in its forwardmost position.

Carried by the forward end of the piston rod 138 is a transversely extending bar 180 (Figs. 1 and 4) to which are connected rearwardly extending tension springs 182 the rear ends of which are secured to pins extending laterally from the opposite sides of the block 178 so that the springs urge the piston 136 rearwardly. As shown in Fig. 1 the links 86 project downwardly below their pivotal connections with the arms 88, 90, the arrangement being such that with the slide 42 in its lowermost position these downwardly projecting portions of the links 86 are in the path of movement of the ends of the bar 180. Consequently upon admission of pressure fluid into the cylinder 134 causing forward movement of the piston 136, which movement cannot take place until the slide 42 has completed its downward movement by reason of the locking engagement of the pawl 140 with the collar 124 on the stem of valve member 116, the bar 180 moves into locking engagement with the lower ends of the links 86 thus locking the slide 42 and with it the diaphragm support 24 in its down position.

During this portion of the operation the vertically movable stop 168 prevents rearward movement of the valve member to provide communication between the pipe 128 and the pipe 132 so that pressure cannot be applied behind the diaphragms 10 and 12 until the diaphragm 12 is in operative relation to the diaphragm 10. The stop 168 is moved downwardly, however, after the slide 42 reaches its lowermost position and is locked therein by the bar 180. For this purpose the bar 180 carries a roll 184 which cooperates with an arm 186 pivoted at 188 to the lower end of the stop 168 and pivoted at 190 to the base of the machine. With the piston 136 in its rearward position the roll 184 holds the arm 186 in a substantially horizontal position so that the stop 168 is in the path of movement of the collar 124 carried by the stem of the valve member 116. The forward end of the arm 186 is cut away at 192 so that when the roll 184 moves into its forward position as shown in Fig. 4 it permits the forward end of the arm 186 to drop sufficiently to withdraw the stop 168 from engagement with the collar 124.

The operator may now move the valve member 116 to its rearmost position permitting communication between pipe 128 and pipe 132 to supply pressure fluid to the chambers 14 and 28 forcing the transfers into intimate contact with the work.

After the pressure has been applied for a suitable length of time the operator releases the knob 118 whereupon the valve member 116 is moved forwardly by the spring 120. The pipes 130 and

132 are now placed in communication with an exhaust port 194 in the rearward end of the valve housing permitting exhaust of the pressure fluid from the pressure chambers 14, 28 and from the cylinder 134. To insure that the pressure in the chambers 14 and 28 will drop sufficiently before the slide 42 moves upwardly so as to eliminate danger of the diaphragms 10, 12 being ruptured when they are separated, the return movement of the piston 136 is retarded sufficiently so that the bar 180 will not move out of locking engagement with the lower ends of the links 86 prematurely. For this purpose the pipe 130 has in it a restriction 196 which is by-passed by a check valve 198 which permits free flow of pressure fluid into the cylinder 134 but the check valve prevents return flow through it so that the fluid exhausting from the cylinder must pass through the restriction 196. During this return movement of the piston the pipe 30 is cut off from the source of suction by movement of the piston rod 138 which carries the port 170 out of register with the ports 174, 176 in the block 178.

If the pivotal connections of the links 86 with the arms 88, 90 are at or beyond dead center position with respect to the shaft 92 and pins 94 it will be necessary to move the links manually past dead center before the spring 68 is effective to raise the slide 42. Accordingly, a lever 200 (Fig. 2) carried by the side of the machine base is provided, this lever having a portion 202 engageable with the arms 88, 90 at that side of the machine so that upon depression of the forward end of the lever the arms are moved in a counter-clockwise direction sufficiently to permit the slide 42 to be moved upwardly by the spring 68. A spring 204 normally holds the lever 200 in the position shown in Fig. 2 with the portion 202 in engagement with a stop screw 206.

It is sometimes desirable to apply a water spray to either or both of the diaphragms prior to the application of pressure therethrough to the work. For this purpose water jets 208, 210 (Fig. 2) are provided, the former being arranged to spray upwardly and the latter downwardly. The jet 208 is supported by a pipe 212 connected to a T-junction 214 while the jet 210 is supported by a pipe 216 connected to the junction 214, there being a suitable shutoff 218 in the pipe 216 so that the pipe 208 may be operated alone if desired. A pipe 220 connects the bottom of the T-junction 214 to a water valve 222 into which water under pressure is supplied through a pipe 224. Opening of the valve 222 to admit water to the jets is effected by rearward movement of a lever 226 pivoted at 228, the valve 222 normally being held closed by a spring (not shown).

Projecting forwardly from the upper end of the lever 226 are spaced ears 230 (Fig. 3) between which is pivoted an arm 232. This arm carries a roll 234 arranged for engagement by a curved arm 236 (Fig. 2) carried by one of the arms 86, the arrangement being such that as the arms 88, 90 are rotated in a clockwise direction, as viewed in Fig. 2, during downward movement of the slide 42, the arm 236 engages the roll 234 and moves it rearwardly moving the lever 226 rearwardly to open the valve 222. As shown in Fig. 3 the arm 232 carrying the roll 234 has a flat portion 238 cooperating with a correspondingly flattened surface between the ears 230 so that the arm 232 cannot rotate in a counterclockwise direction beyond the position shown in Fig. 3. Consequently, upon rearward movement of the roll 234 the lever 226 is moved therewith as a unit. As the slide 75

42 continues its downward movement the arm 236 moves out of contact with the roll 234 permitting closure of the valve 222 so that the water is sprayed on the diaphragms for a short period only.

The sprays 208, 210 may if desired be manually controlled at the will of the operator. For this purpose the arm 232 is swung upwardly into the broken line position of Fig. 2. The roll 234 is carried by the arm 232 on a pin 240 which projects laterally beyond the arm to engage a slot 242 in the rearward end of a link 244, the forward end of which is pivoted to one end of a lever 246. The other end of this lever is connected by a link 248 to a lever 250 pivoted at 252 to the base of the machine. By moving the upper end of the lever 250 rearwardly against the action of a light spring 254 the link 244 is moved forwardly so that the arm 232 may be swung upwardly to bring the pin 240 into alignment with the slot 242. Upon release of the handle the parts move into the positions shown in Fig. 2. If now the operator moves the lever 250 rearwardly still further which movement is normally opposed by the spring in the valve 222, the lever 226 is moved to open the valve and admit water to one or both of the sprays 208, 210. Upon release of the lever 250 the spring within the valve 222 returns the parts to the positions shown. With the arm 232 in its broken line position as shown in Fig. 2 it will be understood that it is out of the path of movement of the curved arm 236 so that the sprays will not be operated automatically in the downward movement of the slide 42.

Referring now to Fig. 10, upper and lower diaphragms 256, 258 are provided, which are pre-shaped generally in accordance with the contour of a saucer blank. Each of these diaphragms comprises a layer of substantially nonporous rubber 260 to the work contacting face of which is cemented or otherwise suitably secured a layer of sponge rubber 262. The sponge rubber presents a pitted surface which assists in the dissipation of any air pockets which may be present between the rubber and the work thus insuring good overall contact between the work and the rubber.

Fig. 11 illustrates diaphragms 264, 266 having sponge rubber facings 268, 270, the diaphragms being suitably shaped to accommodate a cup blank. It will be noted that the lower diaphragm 266, 270 has a suitably shaped recess to accommodate the handle of the blank.

In the operation of the machine a transfer is placed upon the work piece which is then placed upon the lower diaphragm while the upper diaphragm is in the elevated position shown in Fig. 2. In the event that the work piece is a plate blank it may be that a transfer will be applied only to its upper surface in which case the arm 232 will be disconnected from the link 244 so that the jet 208 operates to spray the upper diaphragm automatically upon downward movement of the slide 42 the jet 210 being shut off at 218. If, however, the work piece is to have transfers applied to both sides as may be the case in a blank for a cup it may be desirable to spray both the upper and lower diaphragms in which case the jet 210 will be rendered operative and the arm 232 moved into the broken line position in Fig. 2 and connected with the link 244. The hand lever 250 will then be operated prior to insertion of the work in the machine to cause both diaphragms to be sprayed with water.

With the work piece P placed on the lower diaphragm the lever 166 (Fig. 1) is depressed to open the valve 162 and admit fluid pressure into the pipe 82 which thereupon acts upon the piston 80 causing the slide 42 to be lowered against the action of the spring 68. The slide moves downwardly into the position shown in Fig. 4 at which time the work piece is engaged by the upper and lower diaphragms, there being formed around the work piece an annular space in communication with the pipe 30. During this downward movement of the slide 42 the shaft 92 turns through approximately 180° until the lower portions of the links 86 move into engagement with adjustable stop screws 272 carried by the base 36. Rotation of the shaft 92 also causes movement of the pawl 140 into the position shown in Fig. 6 permitting rearward movement of the valve member 116 by the operator. This valve member cannot thus be operated until the upper diaphragm is in its lower position thus insuring against rupture of the diaphragms by the inadvertent premature application of pressure fluid into the spaces behind them.

Upon moving the valve member 116 rearwardly to the position shown in Fig. 4 pressure fluid acts on the piston 136 moving it forwardly so that the pipe 30 is connected to a source of suction and the air between the diaphragms is exhausted. The piston moves forwardly until the bar 180 engages the lower end portions of the links 86 to lock the slide 42 in its down position. At the same time the roll 184 carried by the bar 180 permits the forward end of the arm 186 to drop withdrawing the stop 168 from the path of movement of the collar 124 on the stem of the valve member 116. This stop insures that the upper diaphragm 12 and its support 24 with the slide 42 are locked in their down positions before the valve 112 can be operated to supply fluid pressure behind the diaphragms. The valve member 116 can now be moved to its rearmost position whereupon pressure fluid flows into the chambers 14, 28 through pipes 106, 96 respectively so that the design on the transfer is suitably impressed upon the blank.

After a suitable interval the operator releases the knob 118 permitting forward movement of the valve member under the influence of the spring 120. The chambers 14 and 28 are now placed in communication with the exhaust port 194 as in the cylinder 134. However, the pressure will drop in the chambers 14, 28 more rapidly than in the cylinder 134 because the pressure fluid must pass from the cylinder through the restriction 196. As soon, however, as the pressure has dropped sufficiently in the cylinder 134 the piston is moved rearwardly by the springs 182 withdrawing the bar 180 from locking engagement with the lower ends of links 86 permitting upward movement of the slide 42. This upward movement may be initiated if necessary by depression of the lever 200.

During the first part of the counterclockwise rotation of the shaft 92 (Fig. 4) the pawl 140 and the collar 142 (Fig. 7) move as a unit under the action of the ball 144 in the groove 156, until the ball 146 enters the groove 154. At this time the nose portion of the pawl engages the collar 124 as shown in Fig. 5 and the collar 142 completes its turning movement without the pawl 140. Thus upon return of the parts to the positions shown in Fig. 7 the pawl 140 is locked by engagement of the ball 146 in the groove 154 in a position to obstruct depression of the knob 118,

and the pawl can not be accidentally dislodged from this position.

Having thus described the invention what I claim as new and desire to secure by Letters 5 Patent of the United States is:

1. Apparatus for impressing paint from a transfer upon a pottery blank comprising a pair of flexible diaphragms arranged for engagement with opposite sides of a work piece placed therebetween, supports for said diaphragms, said supports providing with said diaphragms closed chambers into which pressure fluid may be admitted to force said diaphragms toward each other to apply pressure to the opposite sides of the work piece placed therebetween, means mounting one of said supports for movements into and out of proximity to the other support to carry its diaphragm into and out of cooperative relation to the diaphragm on the other support, means for admitting pressure fluid into said chambers, and means rendering said last-named means inoperative except when said supports are in proximity to each other.

2. Apparatus for impressing paint from a transfer upon a pottery blank comprising a pair of flexible diaphragms arranged for engagement with opposite sides of a work piece placed therebetween, supports for said diaphragms, said supports providing with said diaphragms closed chambers into which pressure fluid may be admitted to force said diaphragms toward each other to apply pressure to the opposite sides of the work piece placed therebetween, means mounting one of said supports for movements into and out of proximity to the other support to carry its diaphragm into and out of cooperative relation to the diaphragm on the other support, means for locking said one of said supports in proximity to the other support, means for admitting pressure fluid into said chambers, and means rendering said last-named means inoperative prior to operation of said locking means.

3. Apparatus for impressing paint from a transfer upon a pottery blank comprising a pair

4.5 of flexible diaphragms arranged for engagement with opposite sides of a work piece placed therebetween, supports for said diaphragms, said supports providing with said diaphragms closed chambers into which pressure fluid may be admitted to force said diaphragms toward each other to apply pressure to the opposite sides of the work piece placed therebetween, means mounting one of said supports for movements into and out of proximity to the other support to carry its diaphragm into and out of cooperative relation to the diaphragm on the other support, means cooperating with said diaphragms to form a closed chamber therebetween when the diaphragms are in cooperative relation to each other, means for first moving said one of said supports into proximity to the other, means for then withdrawing the air from the chamber between said diaphragms, means for then supplying pressure fluid to the first-named chambers, and means preventing operation of said last-named means until the movable support has moved into proximity to the other support.

4. Apparatus for impressing paint from a transfer upon a pottery blank comprising a pair of flexible diaphragms arranged for engagement with opposite sides of a work piece placed therebetween, supports for said diaphragms, said supports providing with said diaphragms closed chambers into which pressure fluid may be admitted to force said diaphragms toward each

11

other to apply pressure to the opposite sides of the work piece placed therebetween, means mounting one of said supports for movements into and out of proximity to the other support to carry its diaphragm into and out of cooperative relation to the diaphragm on the other support, fluid-pressure-operated means for moving one of said supports into proximity to the other support, means for admitting pressure fluid into said chambers, and a valve movable into one position to supply pressure fluid to said fluid-pressure-operated means and into a second position to supply pressure fluid to said chambers.

5. Apparatus for impressing paint from a transfer upon a pottery blank comprising a pair of flexible diaphragms arranged for engagement with opposite sides of a work piece placed therebetween, supports for said diaphragms, said supports providing with said diaphragms closed chambers into which pressure fluid may be admitted to force said diaphragms toward each other to apply pressure to the opposite sides of the work piece placed therebetween, means mounting one of said supports for movements into and out of proximity to the other support to carry its diaphragm into and out of cooperative relation to the diaphragm on the other support, fluid-pressure-operated means for moving said one of said supports into proximity to the other support, means for admitting pressure fluid into said chambers, a valve movable into one position to supply pressure fluid to said fluid-pressure-operated means and into a second position to supply pressure fluid to said chambers, and means preventing movement of said valve into said second position until the movable support has moved into proximity to the other support.

6. Apparatus for impressing paint from a transfer upon a pottery blank comprising a pair of flexible diaphragms arranged for engagement with opposite sides of a work piece placed therebetween, supports for said diaphragms, said supports providing with said diaphragms closed chambers into which pressure fluid may be admitted to force said diaphragms toward each other to apply pressure to the opposite sides of the work piece placed therebetween, means mounting one of said supports for movements into and out of proximity to the other support to carry its diaphragm into and out of cooperative relation to the diaphragm on the other support, means for moving said one of said supports toward the other support, means for admitting pressure fluid into said chambers, means preventing admission of pressure fluid into said chambers until said movable support is in operative relation to said other support, and means preventing separation of said supports until the pressure fluid has been exhausted from said chambers.

7. Apparatus for impressing paint from a transfer upon a pottery blank comprising a pair of flexible diaphragms arranged for engagement with opposite sides of a work piece placed therebetween, supports for said diaphragms, said supports providing with said diaphragms closed chambers into which pressure fluid may be admitted to force said diaphragms toward each other to apply pressure to the opposite sides of the work piece placed therebetween, means mounting one of said supports for movements into and out of proximity to the other support to carry its diaphragm into and out of cooperative relation to the diaphragm on the other support, a

12

sealing ring associated with the periphery of one of said diaphragms and cooperating with the other diaphragm to form a closed work chamber between the diaphragms when the diaphragms are in operative relation to each other, means for exhausting air from said work chamber, means for admitting pressure fluid to said first-named chambers, and means preventing operation of said last-named means until the air has been exhausted from the work chamber.

8. Apparatus for impressing paint from a transfer upon a pottery blank comprising a pair of flexible diaphragms arranged for engagement with opposite sides of a work piece placed therebetween, supports for said diaphragms, said supports providing with said diaphragms closed chambers into which pressure fluid may be admitted to force said diaphragms toward each other to apply pressure to the opposite sides of the work piece placed therebetween, means mounting one of said supports for movements into and out of proximity to the other support to carry its diaphragm into and out of cooperative relation to the diaphragm on the other support, fluid-pressure-operated means for moving said one of said supports into proximity to the other support, means for admitting pressure fluid into said chambers, and a valve movable into one position to connect the space between said diaphragms to a source of suction and into a second position to supply pressure fluid to said chambers.

9. Apparatus for impressing paint from a transfer upon a pottery blank comprising a pair of flexible diaphragms arranged for engagement with opposite sides of a work piece placed therebetween, supports for said diaphragms, said supports providing with said diaphragms closed chambers into which pressure fluid may be admitted to force said diaphragms toward each other to apply pressure to the opposite sides of the work piece placed therebetween, means mounting one of said supports for movements into and out of proximity to the other support to carry its diaphragm into and out of cooperative relation to the diaphragm on the other support, fluid-pressure-operated means for moving said one of said supports into proximity to the other support, means for admitting pressure fluid into said chambers, a valve movable into one position to connect the space between said diaphragms to a source of suction and into a second position to supply pressure fluid to said chambers, and means preventing movement of said valve into the first position until the movable support is in operative relation to the other support.

10. Apparatus for impressing paint from a transfer upon a pottery blank comprising a pair of flexible diaphragms arranged for engagement with opposite sides of a work piece placed therebetween, supports for said diaphragms, said supports providing with said diaphragms closed chambers into which pressure fluid may be admitted to force said diaphragms toward each other to apply pressure to the opposite sides of the work piece placed therebetween, means mounting one of said supports for movements into and out of proximity to the other support to carry its diaphragm into and out of cooperative relation to the diaphragm on the other support, fluid-pressure-operated means for moving said one of said supports into proximity to the other support, means for admitting pressure fluid into said chambers, a valve movable into one position to connect the space between said diaphragms to a source of suction after the mov-

13

able support is in operative relation to the other support and into a second position to supply pressure fluid to said chambers, and means controlling the movement of said valve to insure the above sequence of operations.

11. Apparatus for impressing paint from a transfer upon a pottery blank comprising a pair of flexible diaphragms arranged for engagement with opposite sides of a work piece placed therebetween, supports for said diaphragms, said supports providing with said diaphragms closed chambers into which pressure fluid may be admitted to force said diaphragms toward each other to apply pressure to the opposite sides of the work piece placed therebetween, means 15 mounting one of said supports for movements into and out of proximity to the other support to carry its diaphragm into and out of cooperative relation to the diaphragm on the other support, fluid-pressure-operated means for moving said one of said supports into proximity to the other support, means for admitting pressure fluid into said chambers, a valve movable into one position to connect the space between said diaphragms to a source of suction and into a second position to supply pressure fluid to said chambers, and means operative upon return movement of said valve to exhaust the air between said chambers before permitting separation of said supports.

12. Apparatus for impressing paint from a transfer upon a pottery blank comprising upper and lower flexible diaphragms for operating upon opposite sides of a work piece placed therebetween, supports for said diaphragms, means for moving one of said supports toward and away from the other support, a spray nozzle directed toward the diaphragm carried by the upper support when the supports are separated, and means operative in response to movement of said one of said supports toward the other support for 40 momentarily connecting said nozzle to a source of water.

13. Apparatus for impressing paint from a transfer upon a pottery blank comprising upper and lower flexible diaphragms for operating upon 45 opposite sides of a work piece placed therebetween, supports for said diaphragms, means for moving the upper support toward and away from the lower support, a spray nozzle directed toward the diaphragm carried by the upper support when the support is in a raised position, means operative in response to downward movement of the upper support for momentarily connecting said nozzle to a source of water, means rendering said

14

last-named means inoperative, and means for manually connecting said nozzle to the source of water.

14. Apparatus for impressing paint from a transfer upon a pottery blank comprising upper and lower flexible diaphragms for operating upon opposite sides of a work piece placed therebetween, supports for said diaphragms, means for moving the upper support toward and away from the lower support, a spray nozzle directed toward the diaphragm carried by the upper support when the support is in a raised position, means operative in response to downward movement of the upper support for momentarily connecting said nozzle to a source of water, means rendering said last-named means inoperative, means for manually connecting said nozzle to the source of water, and a second nozzle connected to said first nozzle to be controlled therewith, said second nozzle being directed toward the diaphragm on the lower support.

15. Apparatus for impressing paint from a transfer upon a pottery blank comprising upper and lower flexible diaphragms for operating upon opposite sides of a work piece placed therebetween, supports for said diaphragms, means for moving the upper support toward and away from the lower support, a spray nozzle directed toward the diaphragm carried by the upper support when the support is in a raised position, means operative in response to downward movement of the upper support for momentarily connecting said nozzle to a source of water, and means operative when the upper support is in its lower position for directing pressure fluid to said diaphragms to force them toward each other and into engagement with opposite sides of the work piece therebetween.

NORMAN VICTOR GERMANY.
